UNITED STATES PATENT OFFICE.

LLEWELLYN A. MORRISON AND JOHN LARSEN, OF TORONTO, CANADA;
SAID LARSEN ASSIGNOR TO SAID MORRISON.

MACHINE FOR MANUFACTURING VENEERS.

SPECIFICATION forming part of Letters Patent No. 567,153, dated September 8, 1896.

Application filed February 7, 1893. Serial No. 461,403. (No model.)

To all whom it may concern:

Be it known that we, LLEWELLYN A. MORRISON and JOHN LARSEN, of the city of Toronto, in the county of York, in the Province 5 of Ontario, Canada, have invented a certain new and Improved Machine for the Manufacture of Veneers, of which the following is a specification.

The object of the invention is to produce a 10 veneer-cutting machine in which the angle of the veneer-knife may be altered to suit the thickness of the veneer to be cut without moving the cutting edge of the said knife, and to arrange, in connection with the veneer- 15 machine, a crosscut-knife which will automatically cut the sheets of veneer into predetermined lengths; and it consists, first, of a veneer-knife having its cutting edge set on a line leading to the center of the log and 20 carried on a circular bearing having the cutting edge of the knife as the center of its circle; second, of a crosscut-knife provided with mechanism arranged in connection with the veneer-machine, so that the movement 25 of the veneer shall put the mechanism into action at predetermined periods, so as to cut the sheet-veneer into predetermined lengths, the machine being otherwise constructed in detail as hereinafter more particularly 30 explained, and then definitely claimed.

In the accompanying drawings, Figure 1 is a perspective view of our improved machine. Fig. 2 is an enlarged cross-section of the veneer-knife and its supports. Fig. 3 is 35 an enlarged perspective detail of the gearing for feeding the carriage. Fig. 4 is a perspective view of the scarfing-carriage. Fig. 5 is a cross-section of the scarfing-carriage and the log on the line x x , Fig. 4. Fig. 6 is a 40 sectional elevation of the clutch-pulley. Fig. 7 is a sectional elevation showing the ball-journal on the log-spindle. Fig. 8 is a perspective view of a crosscut-knife and mechanism connected therewith. Fig. 9 is an end 45 section of the crosscut-knife. Figs. 10, 11, and 12 are details of the friction-pulley. Fig. 13 is a view showing the connection between the veneer and crosscut-knife.

A represents the main frame of the machine; B, the carriage; C, the block or frame

by which the veneer-knife D is supported. Each end of this block or frame C is shaped on a circle and rests upon a block E, formed on a circle and fixed to the carriage B. The face of each block E and bottom of the block 55 C, resting thereon, are shaped on a circle struck from the cutting edge of the knife D. Consequently by moving the block or frame C in its supports the angle of the veneer-knife D may be altered without moving the cutting 60 edge of the said knife. The angle of the block or frame C is adjusted by the movement of the set-screws F, the jam-nuts G being employed to lock the frame C when it has been set at its proper angle. As the cutting 65 edge of the knife is the center of the circle on which the bearing is formed and as the said cutting edge is set on a line leading to the center of the log any adjustment of the angle of the knife for the purpose of cutting thin or thick veneer is accomplished 70 without moving the position of the cutting edge. The cutting of the knife will remain the same whether in removing a thin or a thick veneer.

H is a pressure-bar slidingly supported upon the block or frame C. A worm-wheel I, connected to a spindle and situated one at each end of the frame C, is connected by means of a nut to the pressure-bar H in such a manner that the revolving of the worm-wheel I adjusts the pressure-bar H toward or away from the log. A spindle J is supported, as indicated in Fig. 1, which has two worms K formed on it to engage with the worm-wheels 85 I. On one end of the spindle J we place a crank or hand wheel L in order that the operator of the machine may easily adjust the pressure-bar H to suit the thickness of the veneer to be cut.

In order to cut veneer into the proper lengths, we place a scoring knife or knives M (see Fig. 2) on the pressure-bar H and adjust it so that it will cut through the sheet of veneer being cut and which passes between the 95 pressure-bar H and the back of the knife D.

On reference to Figs. 1, 4, and 5 the position and operation of the scarfing-knife N will be understood. This scarfing-knife is fixed on the spindle O, which is pivoted or 100

journaled in the frame or bracket P, suitably connected and carried by the pressure-bar H. Q is a bar connected to the spindle O and designed to rest upon the spindle R, by which the log is supported. S is a spring connected to the swinging frame by which the knife N is carried. This spring is acted upon by a set-screw T, so that the depth of the cutting made by the knife may easily be regulated. The scarfing-knife N is placed in the proper position and set at the proper angle to bevel or scarf the end of the log, and the bar Q rests upon the spindle R, by which the log is supported, and the scarfing-knife is held at the proper relative angle to the circumference of the log during the whole time that the sheet of veneer is being cut off.

In Fig. 7 we show a sectional detail to illustrate the antifriction-bearing which we provide to resist the thrust or back pressure upon the end of the spindle R. This spindle, it will be observed on reference to Fig. 7, passes through a sleeve U, which is supported by the frame A. The outer end of the sleeve U carries a threaded spindle R², which is screwed through a nut V, formed on or connected to the interior of the spindle R. The spindle R² is held from end motion by the hub of the hand-wheel U² and the collar U³. It will be seen from this construction that the spindle R may be readily adjusted lengthwise and that its thrust is entirely conveyed to the sleeve U. Between the flange W, on the end of the sleeve U, and the face of the frame A we place three annular plates or rings a, b, and c. The plates a and c are preferably made of hardened steel and the plate or ring b of brass. This latter ring has a series of holes d, (see Fig. 7,) which are arranged as shown zigzag around the center of the plate or ring c, as shown. Into each of these holes d we insert a small ball e, preferably made of hard steel and projecting slightly through both sides of the plate b, so that the plate a and c will fit against the balls e when they are brought together, as indicated in Fig. 7. By providing the balls e in the position indicated, the weight of the back thrust on the spindle R will be entirely carried by them, and as they are arranged so that they do not follow each other the surfaces of the plates a and c will not be channeled by the action of the balls as much as it would be if the balls were arranged in line, and it will be found that the friction from the said back pressure will be imperceptible.

X is a rod suitably supported in bearings in the frame A and provided with two miter-pinnions Y, arranged to mesh with miter-wheels Z, which are fixed to the screw-spindles by which the carriage B is adjusted. Near the end of the rod X, which is divided, as indicated in Fig. 6, we fix a clutch A', and opposite to the clutch A' we loosely journal a similar clutch B', which is driven by an independent belt. (Not shown in the drawings.) Be-

tween the clutches A' and B' we place the movable clutch C', which is held to the rod X by a feather-key (not shown) and which permits it to be longitudinally adjusted on the rod X. The two ends of the clutch C' are shaped to engage with either of the two clutches A' and B'. As shown in Fig. 1, they are engaged with the clutch A'. Consequently the rod X is made to revolve in the direction necessary to move the carriage B toward the log. This motion is produced from the main shaft by means of the gearing shown in Figs. 1 and 3, which is sufficiently clear in the drawings to avoid the necessity of further description in the specification, particularly as we do not claim anything peculiar in the said gearing; nor do we claim anything very special in the clutch, but, however, we do claim some originality in the mechanism we use for moving the clutch C', by which the motion of the carriage is automatically arrested.

On reference to Fig. 3 it will be observed that we provide a forked rod D', which engages with the groove E', (see Fig. 6,) formed in the clutch C'. This rod is pivoted at f and extends back over the rock-shaft F'. On this rod we fix a dog g, which serves as a lock to hold the forked rod D' in position while the gearing is in action. A spring h is fixed to the rod D' and is set so as to fit below the dog g, so that the rod D' shall be held against the said dog.

G' is a crank fixed to the rock-shaft F', and from this crank G' we carry a rod H'. A collar j is formed on the rod H'. When the carriage by which the knives are supported has been fed in as far as desired, it comes in contact with the collar j, which pushes the crank G' over and carries the dog g clear of the forked rod D', which will immediately spring past the said dog by the action of its spring h and thus carry the clutch C' clear of the clutch A', and thus stop the forward movement of the carriage. The clutch C' is run by an independent belt in the opposite direction to that in which the clutch A' is caused to revolve. In order to cause the carriage to travel back, the clutch C' is moved so as to engage with the clutch B'.

The foregoing is a description of the mechanism we employ for cutting the veneer from the log, and as it is necessary or advisable to cut the sheets of veneer into predetermined sizes we provide the following mechanism to work in connection with the mechanism just described.

Fig. 8 is a perspective view of the crosscut-knife.

The side frame 2 is suitably connected to support the following parts:

3 is the bed-plate, provided with the bearing-boxes 4. In these bearing-boxes is fitted the shaft 5. The portions of the shaft 5 which fit into the bearing-boxes 4 are concentric with the center of the shaft 5.

6 is the cross-head, arranged to support the

knife 7. Bearing-boxes 8 are made in the cross-head 6 to rest upon and be fitted to the shaft 5. The portions of the shaft 5 which fit into the bearing-boxes 8 are eccentric to the center of the shaft 5. Consequently when the said shaft revolves the cross-head 6 will be caused to rise and fall in proportion to the throw of the eccentric formed on the said shaft 5. In order that the entire weight of the cross-head 6 and its knife 7 shall not be carried by the bearings, we provide springs 9, which are arranged to support the major portion of the weight.

10 is a beam having jaw-shaped ends 11. Each end 11 is connected to its frame 2 by the pin 13, and at each end 11 a block 14 is fitted into the jaw. These blocks 14 are connected, respectively, to each end of the cross-head 6 by means of a pin 15. The projection 16 is made on the end of the cross-head 6 and is flexibly connected to the short shaft 17, which is movably connected to the block 18, formed upon or attached to the end of the vertical shaft 19, which is geared, as indicated in Fig. 8, to the shaft 5. The block 18 acts as a crank upon the shaft 19, and as the short shaft 17 is adjustable in the said block the length of the throw of the crank may be altered to give the length of the stroke to the 30 knife desired. As the beam 10 is pivotally connected to the frame 2 and the cross-head 6, carrying the knife 7, is pivotally connected to the blocks 14 in the beam 10, the said cross-head with its knife will move freely without 35 fear of any binding or straining of the parts. On the bottom of the beam 10 we connect by clamps 20 a piece of hard wood 21, which acts as a cutting-block against which the knife 7 acts while cutting the sheet of veneer which 40 is carried between the said knife 7 and beam 10. Owing to the arrangement of the parts described, when the shaft 5 revolves the eccentric portion of the said shaft imparts, as before described, an upward and downward 45 movement to the knife 7, and a longitudinal movement is simultaneously imparted to the said cross-head, and as the knife 7 is carried by the said cross-head a similar cutting movement is imparted to the said knife, causing 50 the knife at each revolution to act upon the veneer carried past it.

On reference to Fig. 9 it will be observed that an extension-piece 22 is formed on the cross-head 6 to form a back for the knife 7, 55 and to this back 22 we pivot one or more spindles 23 to fit into springs 24, thereby forming flexible supports to the extension-piece of the cross-head 6 in order that the said cross-head may be supported and yet move 60 freely in the different positions required. In order that the knife 7 will only act at predetermined periods, we provide the following mechanism, by which the cross-cutting machine is thrown into action when required by 65 the movement of the veneer leaving the veneer machine: A pulley 25 is loosely jour-

naled upon the shaft 5, and has a projecting rim into which the following clutch mechanism is inserted. This consists of half-rims 26. In the center of each half-rim 26 a projection 27 is placed, and from this projection a pin 28 extends and fits into one of the arms of the spider 29. (See Fig. 11.) To each projection 27 two springs 30 are connected at one end, the other end of each spring being 70 connected to the spider 29, the tension of the said springs holding them close together, so that the outer periphery of the half-rims 26 shall not be in contact with the inner circumference of the pulley 25. Consequently the 80 said pulley 25 will continue to revolve freely until the rim 26 is brought into contact with it. On the inside of each half-rim 26 a lug 31 is formed, and through each of these lugs a set-screw engaging the end of the pivoted 85 dog 32 is placed.

On the end of the arm 33 of the spider 29 we pivot a fly 34, and on the end of its pivot we connect an arm 35, and the other end of the said arm is connected to the plate 36, 90 which is attached to or forms part of the hollow sleeve 37, (see Fig. 12,) in which sleeve a spiral spring 38 is placed, one end of this spring being fixed to the sleeve 37, which is loose on the shaft 5, and the other end to a 95 collar 39, which is secured to the shaft 5.

40 is an arm connected to the sleeve 37 and extending behind the stop 41. The normal position of this stop is in the path of the arm 40, and so long as the stop 41 remains in this 100 position it resists the strain of the spring 38, and the fly 34 is held in such a position as to be clear of the dogs 32, and the rims 26 remain clear of the pulley 25. The moment that the stop 41 is moved clear of the arm 40 105 the spring 38 immediately causes the sleeve 37 to revolve in the direction of the arrows, thus moving the arms 32 by means of the arms 35 and flies 34, and pulling the half-rims 26 apart and pressing them against the 110 interior surface of the pulley 25, thereby connecting the said pulley 25 to the shaft 5 and causing the said shaft to revolve. By the time that the shaft 5 has made one revolution the stop 41 has by its spring 42 returned 115 to its initial position in the path of the arm 40, arresting the motion of the said arm and consequently of the sleeve 37, thereby moving the arm 33 so as to throw the fly 34 clear of the dogs 32, thereby permitting the springs 120 30 to draw the rims 26 together, clear of the interior surface of the pulley 25, consequently arresting the motion of the shaft 5. Simultaneously with the arm 40 coming in contact with the stop 41 the arm 43 strikes the said 125 stop, and as this arm 43 is fastened to the shaft 5 the said shaft is thereby prevented being acted upon by the spring 38.

Various devices may be arranged to cause the stop 41 to be tripped, but the following 130 will be found a simple device: On reference to Fig. 13 a trigger 44 will be observed located

at the end of the veneer 45, which, as shown in this figure, has been cut by the veneer-machine and carried over the knife 7. By the time that it has reached the trigger 44 it is 5 time that the sheet should be cut off, to do which it is necessary to start the mechanism by which the knife 7 is operated. It will be noticed that the trigger 44 is pivoted on the end of a rod 46 and that this trigger is connected to the horizontal rod 47, so that when the veneer 45 pushes against the trigger 44 the rod 47 is rolled so as to throw the arm 48 (see Fig. 10) down, and as this arm 48 is connected to the stop 41 by the spring-dog 49 the 10 said stop 41 is drawn down clear of the arm 40, thereby bringing the clutch mechanism into contact with the pulley 25 and thus cause, as already described, the shaft 5 to revolve. The moment that the stop 41 is carried clear 15 of the arm 40 the said arm strikes the dog 49, throwing it off the stop 41, which is instantly brought back into its initial position by the action of its spring 42. The moment that the 20 clutch mechanism already described is carried clear of the pulley 25 the action of the knife 7 is stopped until sufficient veneer has 25 passed it to strike the trigger 44, when the cutting action is once more started. It will 30 of course be seen that by moving the trigger 44 the length of the sheet to be cut off may be altered.

What we claim as our invention is—

1. In a veneer-machine, and in combination with log-supporting means and the pressure-bar, of a swinging frame, a scarfing-knife pivotedly supported in the frame, a spring secured to the said frame and bearing on the knife, and an adjusting-screw to set against the spring and adjust the cut of the knife, substantially as shown and described.

2. In a veneer-machine, and in combination with log-supporting means and the pressure-bar, of a frame pivotedly supported on the pressure-bar, a scarfing-knife pivotedly supported in the said frame, a spring to bear on the knife, an adjusting-screw to set against the spring to adjust the cut of the knife, and means for automatically adjusting the knife to keep it at the same angle to the log as the 45 log decreases in size, substantially as shown and described.

3. In a veneer-machine, the combination of a shaft having bearings concentric to the axis thereof, and portions intermediate of the bearings thereof eccentric thereto, a cross-head having bearings on the eccentric portions of the shaft and formed with a back piece, a knife seated in the back piece, and yielding supports connected to the back piece, whereby 55 the cross-head is supported to move freely in its different positions, as specified.

4. The combination with the knife-operating shaft having an eccentric portion, the cross-head and knife operated thereby, said 60 knife being carried and supported by the cross-head, of springs 9 arranged under the

cross-head, one end of said springs being connected to a laterally-projecting portion of said cross-head and the other end to a projecting portion on the base of the machine-frame, substantially as shown and described.

5. In a veneer-machine, the combination of the beam 10, having jaw-shaped ends 11, supported on pins 13, and provided with a buffer-strip of wood 21 fixed to the bottom edge 75 of the beam, a vertically-reciprocating cross-head 6 having the ends arranged to slide in the jaws on the beam ends, a knife secured to the cross-head, and means to reciprocate the cross-head, substantially as shown and 80 described.

6. In a veneer-machine, a knife for cutting the veneer into predetermined lengths, mechanism for operating said knife, and a clutch for putting said mechanism into and out of 85 gear, a stop 41 acting on said clutch to hold the knife in an inoperative position, a rock-shaft provided with means for moving said stop, and a trigger having a connection with 90 said rock-shaft and arranged to be struck and moved by the veneer, thereby rocking said shaft and cutting said veneer, substantially as described.

7. In a veneer-machine, a knife arranged to cut the veneer into predetermined lengths, 95 a driving-shaft 5, having a spider fixed thereto and adapted to operate said knife, a pulley loosely journaled on said shaft and provided with a projecting rim, half-rims connected to said spider and held inside of 100 said pulley, springs 30 normally holding the rims together, flies connected with the spider and adapted to separate the half-rims, arms 35, each having one of its ends connected to one of the flies and its other end to a sleeve 105 on said driving-shaft, a spring having one end connected to said sleeve and its other end having a connection with said shaft, an arm 40 projecting from the said sleeve and a stop in the path of said arm, in combination 110 with means for moving said stop arranged to be operated by the veneer as it leaves the machine, substantially as and for the purpose specified.

8. In a veneer-machine, a knife arranged 115 to cut the veneer into predetermined lengths, a driving-shaft having a pulley thereon and arranged to operate said knife, a clutch mechanism within said pulley adapted to start and stop said shaft, an arm 40 depending from 120 said mechanism, and a stop 41 in the path of the stop 40 arranged to keep the driving-shaft inoperative, in combination with mechanism arranged in the path of the veneer as it leaves the cutting apparatus and constructed to 125 move the stop 41 by the action of the veneer when leaving the machine, whereby the driving-shaft is operated and the veneer cut, substantially as described.

9. In a veneer-machine, a knife arranged 130 to cut the veneer into predetermined lengths, a driving-shaft having a pulley thereon and

arranged to operate said knife, a clutch mechanism within said pulley adapted to start and stop said shaft, an arm 40 depending from said mechanism, and a stop 41 in the path of 5 said stop 40, in combination with the rock-shaft 47, arm 48 connected thereto, and a trigger 44 having a connection with said rock-shaft and arranged in the path of the veneer as it leaves the cutting apparatus and adapted

to be operated by the said veneer, whereby to the driving-shaft is operated and the veneer cut, substantially as described.

Toronto, January 26, 1892.
